UNITED STATES PATENT OFFICE.

LEE C. SHARP, OF PLATTS MOUTH, NEBRASKA, ASSIGNOR TO AMERICAN CAN COMPANY,
OF NEW YORK, N. Y., A CORPORATION OF NEW JERSEY.

CAN-BODY FORMING AND SEAMING MACHINE.

1,017,815.

Specification of Letters Patent.

Patented Feb. 20, 1912.

Application filed November 2, 1909. Serial No. 525,960.

To all whom it may concern:

Be it known that I, LEE C. SHARP, a citizen of the United States, and a resident of Platts Mouth, in the county of Cass and 5 State of Nebraska, have invented certain new and useful Improvements in Can-Body Forming and Seaming Machines, of which the following is a specification.

My invention relates to the manufacture 10 of sheet-metal ware, and especially to machines for forming and side-seaming can-bodies.

It is the object of my invention to provide a machine which will automatically, 15 rapidly and economically perform the operations of removing a body-blank from a magazine, notching the end of the blank, curling the blank into a tubular form,lapping and gaging the lap of the ends of the 20 blank, soldering the lapped portions together, wiping the seam and ejecting the completed body from the machine.

A further object of my invention is to provide mechanism for performing the 25 above functions, which, by a few simple adjustments and without interchanging of parts, may be adapted for making can-bodies of any lengths and diameters within certain established maximum and minimum 30 limits.

A further object of my invention is to provide an improved means for forming the can-body whereby the same is rendered almost perfectly cylindrical and the further 35 operations thereon necessary in completing the can thereby facilitated.

A further object of my invention is to provide means by which the diameter of the can-body is gaged by the length of the sheet 40 or blank instead of being determined by the size and form of the mandrel or part around which the body is held during the soldering of the seam.

Constructions embodying my invention 45 are illustrated in the accompanying drawings, in which—

Figure 1 is a side elevation of the machine, Fig. 2 is front elevation thereof, with portions of the turret mechanism at the rearward part omitted, Fig. 3 is a plan view of 50 the turret and adjoining portions, Fig. 4 is a vertical sectional view taken on the plane of the lines $x-x$ of Figs. 1 and 3, Fig. 5 is an end elevation of one of the carriers, showing 55 the means forlapping and gaging the

lap of the seam, Fig. 6 is a similar view, showing the seam clamped and the body in soldering position, Fig. 7 is a plan view of the feed-table, Fig. 8 is a vertical section through the transverse-feed and the curling devices, the section being on the plane of the line $y-y$ of Fig. 7, Fig. 9 is a detail of the notching device, and Fig. 10 is a longitudinal vertical sectional view of the feed-table, the section being on the plane of the line $z-z$ of Fig. 7.

In the machine shown, I provide a suitable base 1 upon which is mounted the main frame 2. At the front side of the main frame and near the bottom thereof, the transverse driving-shaft 3 is journaled in suitable bearings secured to the frame. Said shaft carries at one end the main driving-pulley 4 and at the other end one of a pair of miter-gears 5 by which it is connected with the longitudinal driving-shaft 6. The latter shaft is journaled at the side of the frame in the same horizontal plane as the shaft 3 and is connected at its rearward end with the vertical driving-shaft 7 by a pair of miter-gears 8.

At the top and front of the main frame 2 is a forwardly extending bracket to the side of which is secured a shelf 9. On said shelf are the standards 10 which support one side of the feed-table 11, the opposite side thereof being supported by the side-plate 12 secured upon the frame as shown. Upon the feed-table adjoining the front edge thereof is arranged the adjustable magazine for the sheet-metal body-blanks upon which the machine operates to form the can-bodies. Said magazine is formed by vertically-extending angle-posts 13, 14, 15 and 16, of which the first is fixedly secured upon the table, the post 14 being connected therewith by horizontal rods 17 so as to be adjustable longitudinally of the table, the post 15 being secured upon the table so as to be adjustable transversely thereof, and the post 16 being adjustably connected with the post 15 by rods 17 similar to those connecting the posts 13 and 14. By the various possible adjustments of the angle-posts the magazine may be adapted to receive body-blanks of any length and width within the capacity of the machine. The body-blanks are disposed in a pile in the magazine and are removed serially from the bottom thereof and carried rearwardly over the feed-table 110

by the following mechanism: Between the bearings of the transverse-driving-shaft 3 a cam 18 is secured to the shaft and said cam is normally engaged by a roller 19 carried by a slotted rod which passes around the shaft at the sides of the cam and extends rearwardly to connect with the lower end of a lever 20 which is fulcrumed inside of the main frame. The upper end 10 of said lever is connected by a rod 21 with a longitudinally movable slide 22 arranged in suitable guideways in the top of the frame 2. To said slide is secured a plate 23 which extends laterally above the shelf 15 9 and carries a roller 24 which rests upon the shelf, as shown. From the plate 23 a standard 25 extends upwardly and carries a horizontally extending threaded rod 26. Said rod passes through lugs formed on the 20 bottom of the feed-slides 27 and 27^a which are held in suitable guideways on the bottom of the feed-table, the rod 26 being adjustably connected with the slides by nuts arranged at each side of the lugs. To the 25 slides 27 and 27^a are pivotally connected the dogs 28 two of which extend up into each of a number of longitudinal slots made in the feed-table. The dogs are normally held in raised position by springs 29 placed under the same, and the elevation thereof is 30 adjusted by means of the screws 30 so that the ends of the dogs will extend above the table sufficiently to engage a body-blank lying thereon. The ends of the dogs, where 35 the same engage the blanks, are provided with renewable hardened wearing-plates 31, as shown in Fig. 10.

By the connections described the cam 18 imparts an intermittent reciprocating movement to the feed-slides, the same being positively actuated in the rearward direction, and returned on the forward stroke by the spring 32 which is connected with the lever 20. At each rearward stroke of the slide 27 45 the set of dogs carried thereby engages the lowermost blank in the magazine and pushes the same out of the magazine to the position A, shown in Figs. 7 and 10. At the next rearward stroke the blank is engaged 50 by the dogs on the rearward slide 27^a and pushed from the position A to the position B upon the rearward portion of the feed-table which will be designated as the transverse-feed-table 33. In the movement of the 55 blank to each of said positions A and B the edge thereof is gaged upon the dogs 28 and any throwing or displacement of the blank away from said dogs is prevented by the following devices: Over the transverse-feed-table 60 are arranged the guide-bars 34, the outer ends of which are supported by a bar 35 connected with the table, the opposite ends of the bars being connected with the flux-tank-bracket 36 carried by the side- 65 plate 12. The front one of said guide-bars

has connected therewith the hinged bars 37 which extend forwardly therefrom and are connected with the drag-plate 38 which rests upon the table at the position shown, and under which the blanks are pushed in moving from the magazine to the position A. In the front guide-bar 34 are arranged a number of vertically-movable spring-impressed pins 39, of which the lower ends are rounded and normally engage the surface 75 of the table, so that the blank in moving to the position B is pushed under them.

During the time that the blank rests at the position A and is held by the drag-plate 38, the end thereof which is to form the inner lap of the body-seam is notched or trimmed off at the corners by the following mechanism: At the side of the feed-table is journaled a small shaft 40 which, near the front end thereof has an arm 41 fixedly secured thereto and which carries on the rearward part an arm 42 adjustable longitudinally thereof. Said arms 41 and 42 extend in over the feed-table and are provided with shearing-plates which are adapted to coöperate with similar plates 43 disposed upon the table, the rearward of said plates being adjustably secured and the front one fixedly secured to the table. The front arm 41 has an outwardly and downwardly extending portion connecting with a rod 44 which extends inwardly and downwardly and has a slotted head thereon passing over the longitudinal driving-shaft 6. A cam 45 secured on the said shaft engages a roller carried by the head and intermittently lifts the rod 44, thus rocking the shaft 40 and causing the shearing-plates to notch or cut off the corners of the blank at the position A.

After the blank reaches the position B upon the transverse-feed-table 33, it is engaged and pushed laterally through the adjustable curling-aperture at the inner end of said table, by the reciprocatable transverse-feed-slide. The said slide comprises a thin top-plate 46 disposed upon the surface of the table under the guide-bars 34, a plurality of fingers 47 connected with said plate and extending down into channels in the table, and a bottom-plate 48 disposed below the 110 table and connected with the top-plate by a member 49 extending through a slot in the table. The feed-slide is given an intermittent reciprocating movement by means of a cam 50 secured on the longitudinal driving-shaft 6, the said cam being engaged by a roller carried on the lower end of a lever 51 which is fulcrumed on a shaft 52 journaled in bearings on the side of the main frame. The upper end of the lever is connected by a rod 53 with the bottom-plate 48 of the feed-slide. The slide is thus positively actuated by the cam during the inward or feeding movement thereof, while the outward or return stroke thereof is 115 120 125 130

imparted by the spring 54, which is connected with an arm 55 secured on the fulcrum-shaft 52 and which extends to an eye-block 56 on the base 1. The adjustable 5 curling-aperture is formed between the inner end of the transverse-feed-table and the end of a block 57 arranged adjoining the same. The said block is mounted upon a shelf or ledge formed on the side-plate 12 10 below the bracket 36 and is connected therewith by means of the adjusting-screws 58 by which the block may be moved toward or away from the end of the table to vary the width of the arcuate slot or aperture 15 between them. The end of the aperture-adjusting-block is channeled similarly to the table 33, the channels, in effect, intersecting the aperture and thus permitting the movement of the feed-fingers 47 to a 20 point beyond the aperture. The ends of the feed-fingers are beveled or rounded backwardly and downwardly so that at the conclusion of the curling operation the rearward end of the blank in passing through 25 the curling-aperture will be substantially perpendicular to the faces of the fingers at the points thereon engaged by the blank.

Below the inner end of the transverse-feed-table adjacent to the curling-aperture 30 is arranged the stationary mandrel 59 which is supported at its front end by a standard 60 extending up from the main frame. In the upper part of said mandrel, a little to one side of a vertical plane passing through 35 the axis thereof, is a longitudinally extending feather 61 which engages the lower side of the table 33 adjoining the curling-aperture, the end of the table below the channels for the feed-fingers being beveled back to 40 said feather, as shown in Fig. 8.

The width of the curling-aperture is so adjusted that when the blank is pushed through the aperture by the feed-fingers it will be uniformly curled or bent so that 45 every part thereof will tend to assume the form of an arc of smaller radius than that of the can-body into which the blank is to be formed. The curling of the blank causes it, after passing through the aperture, to 50 pass around the mandrel 59, as shown in Fig. 8, until the forward end thereof engages the feather 61, and as the rearward end of the blank leaves the curling-aperture the resilience of the curled body causes it 55 to close upon the mandrel so that both ends will engage the feather 61 and the body will hang from the mandrel at the position C shown in Figs. 2 and 10. It should be here noted that the diameter of the mandrel 60 59 is made smaller than that of the smallest can-body which the machine is to produce. For cans of relatively large diameter it may in some cases be necessary to employ the arcuate supporting-plate 62 to prevent 65 sagging of the body. Said plate is adjust-

ably connected with the mandrel-standard 60 by means of a stud passed through a vertical slot in the standard.

After the curling operation is completed and the curled blank hangs upon the mandrel 59 at the position C, as described, it is next engaged by the stripping-fingers 63 and pushed off the stationary mandrel onto one of the carrier-mandrels 64 at the position D. The said stripping-fingers are carried by the slide 22, extending upwardly therefrom and having inwardly-turned ends which extend in toward the mandrel in front of the curled blank at the position C so as to engage the blank during the rearward movement of the slide. During the movement of the blank off the stationary mandrel, flux is applied to the end thereof which is to form the inside lap of the seam, by means of a brush 65 arranged as 80 shown in Fig. 1. Said flux-applying brush is kept moistened with liquid flux supplied from a tank 66 which is supported on the bracket 36 and from which a valve-controlled tube extends to the brush, as shown. 90

At the upper rearward portion of the main frame 2 is a head 67 which carries a vertical sleeve 68 consisting of a tubular portion extending through the head, a horizontal flange portion resting upon and secured to the head, and an upper tubular portion extending above the flange portion. The turret-plate 69 is revolvably mounted upon the said sleeve 68, the hub of the plate inclosing the upper portion of and resting 100 upon the flange portion of the sleeve, as shown in Fig. 4. Upon the lower outer portion of the turret-plate is secured a ring 70 between which and the edge of the plate is formed an annular T-slot. In said T-slot 105 is disposed an arcuate plate 71 from which a connecting-rod 72 extends to the crank-plate 73 carried on the upper end of the vertical driving-shaft 7. The plate 71 carries on the lower side thereof a pawl adapted to engage 110 ratchet-teeth formed at the inner edge of the slot, as represented by dotted lines in Fig. 3. By the reciprocating movement imparted to the said plate 71 by the crank-plate the pawl is intermittently engaged with the ratchet-teeth to advance the turret. Secured upon the upper side of the turret-plate and equidistantly spaced around the outer edge thereof, are the carrier-standards 74 which support the horizontal radially-extending mandrels 64, one of which is brought to the position D adjacent to and in longitudinal alinement with the mandrel 59 at each movement of the turret. 120

Each of the mandrels 64 has a longitudinal vertical slot formed therein in which is disposed the depressible gage-bar 75, the outer end of the slot being covered by a circular plate secured on the end of the mandrel, and the upper edge of the bar being 125 130

beveled as shown. Said gage-bar is yieldably supported by springs 76 arranged in pockets formed in the lower part of the mandrel, the springs tending to hold the bar normally in the raised position shown in Fig. 5, but permitting the same to be depressed until the upper edge thereof lies flush with the surface of the mandrel as shown in Fig. 6. Each of the carrier-stands 10 has a laterally-projecting bracket 77 thereon in which is secured the end of a stud 78 which extends outwardly therefrom and parallel with the mandrel. On said stud is pivotally mounted an arm 79 which 15 carries the clamping-plate 80, said plate extending laterally toward the mandrel and terminating just above the gage-bar 75, as shown. On the arm 79 adjoining the bracket 77 is a finger 81 which is engaged 20 and pushed upwardly by a spring 82 arranged in a recess in the bracket. The strength of said spring is made sufficient to enable the same to turn the arm upon the stud, engage the clamping-plate 80 with the 25 gage-bar 75 and press the same down into the mandrel, overcoming the resistance of the springs 76.

Extending vertically through the sleeve 68 in the frame-head 67, is a tubular shaft 30 83 which carries a laterally projecting arm 84 arranged at the lower end thereof below the bottom of the sleeve 68. Said arm 84 is engaged by a roller carried at the rearward end of a lever 85 which is fulcrumed 35 on the side of the main frame and, extending forwardly therefrom, carries at its front end a roller which engages a cam 86 secured on the transverse driving-shaft 3 adjoining the main driving-pulley 4. Said cam is 40 adapted to impart an intermittent vertical reciprocating movement to the tubular shaft 83. The shaft 83 carries at the upper end thereof a hub 87 from which an arm 88 extends forwardly above the carrier-mandrel 45 which is alined at the position D with the stationary mandrel 59. Through said arm 88 at a position above the carrier-standard, is passed a vertical rod 89 having a head 90 at the lower end thereof, and of which the upper 50 end is threaded and provided with adjusting-nuts 91. A coil spring 92 is arranged around the rod between the head 90 and the lower side of the arm. At one side of the head 90 the gage-plate 93 is secured thereto and extends forwardly therefrom above the carrier-mandrel, the front end of said gage-plate extending through a vertical slot made in the guide-arm 94 formed at the extremity of the arm 88. A laterally-projecting finger 55 95 on the arm 88 carries a vertical rod 96 which is connected with the finger by suitable adjusting-nuts 97. Said rod 96 is arranged at a position such as to enable it to engage the finger 81 of the clamping-arm, 60 to depress the same and raise the clamping- 65

plate 80 out of engagement with the mandrel, as shown in Fig. 5. In the lower part of the head 90 is a pin 98 which is adapted to engage the carrier-standard when the arm 88 is lowered, and to slightly compress the 70 spring 92, sliding the rod 89 up through the arm as represented in Fig. 5.

Referring now to said Fig. 5, the operation of forming and gaging the lap of the body-seam may be understood. When the 75 carrier-mandrel is alined with the stationary mandrel the end of the depressible gage-bar 75 is opposite the end of the feather 61 which separates the ends of the curled body-blank at the position C. After the movement of the turret has ceased and the mandrels are in alined position, the arm 88 is lowered and near the end of said lowering movement, after the bottom of the gage-plate 93 has reached a position adjacent to 80 but not quite touching the mandrel, the pin 98 engages the carrier-standard to stop the plate at said position. Further downward movement of the arm 88 compresses the spring 92 and engages the rod 96 with the 90 finger 81 of the clamping-arm to depress the same and raise the clamping-plate 80 to a position such that a slight clearance space is left between the same and the top of the depressible gage-bar 75. The curled body-blank is then pushed off the stationary mandrel onto the carrier-mandrel as before described, the inside-lap of the body passing 95 under the gage-plate 93 and engaging the inner side of the depressible gage-bar 75. 100 After the body-blank has passed out of engagement with the feather 61 the resilience of the curled blank causes the end thereof to spring in over the beveled upper face of the depressible gage-bar, passing between the 105 same and the clamping-plate, and finally engaging the side of the gage-plate 93, the position then being as shown in Fig. 5. The arm 88 is then raised, and at the beginning of the upward movement the rod 96 releases the clamping-arm which is moved by the 110 spring 82 to engage the clamping-plate with the body-blank adjoining the outside-lap thereof and thereby press the lapped portions into engagement with each other while the lap is still gaged by the plate 93 and the bar 75, the latter being at the same time pressed down into the mandrel. Continued upward movement of the arm 88 raises the 115 gage-plate 93 clear of the mandrel so that the turret may be advanced to carry the lapped and clamped body to the soldering position E and bring the next carrier-mandrel into the position D to receive a curled body-blank from the stationary mandrel. 120

From the hub 87 carried by the vertically reciprocatable shaft 83 an arm 99 extends out horizontally above the carrier-mandrel which carries the lapped body at the soldering position E. The outer end of said arm 125

is radially slotted and in said slot is slidably mounted the head 100 which has removably secured in the lower part thereof the wedge-shaped soldering-iron 101. An oscillating movement is imparted to the soldering-head by means of the connecting-rod 102 which is connected with the upper part of the head and extends to a small crank-plate carried on the upper end of the shaft 103, 5 said shaft extending from the crank-plate down through the tubular shaft 83 and carrying at its lower end a small pulley 104 from which a belt 105 extends to a pulley 106 on the vertical driving-shaft 7. The soldering-iron is heated by means of a gas-burner 107 supported adjacent to one side thereof by a hanger-strap secured to the arm 99, the burner being supplied with gaseous fuel through a flexible tube 108. At the side 15 of the arm 99 opposite the gas-burner a small bracket is secured thereon in which are mounted the corrugated solder-feeding rolls 109. One of said rolls is connected with a ratchet-wheel 110, adjoining which is 20 pivotally mounted an arm 111 carrying a pawl adapted to engage and actuate the ratchet-wheel. The outer end of said pawl-arm is slotted and has adjustably connected therewith a rod 112 which extends downwardly therefrom and at its lower end is adjustably connected with the end of an arm 113 which extends out from a hub 114 carried upon the upper end of the sleeve 68. The said arm 113 carries standards on which 25 is supported a spool 115 of wire-solder. The solder-wire is passed from the spool between the feed-rolls 109 and thence into a guide-tube 116 which is supported by an arm 117 secured upon the arm 99, and which 30 extends to a point adjacent to the lower edge of the soldering-iron, as shown in Fig. 6. At the conclusion of each downward movement of the tubular vertically-reciprocatable shaft 83 which carries the hub 87 and the 35 arms 88 and 99, the soldering-iron is engaged with the lapped portion of the body, as represented in Figs. 1 and 6. By said downward movement of the arm 99 which carries the soldering devices, the feed-rolls 40 109 are also actuated to feed a portion of the solder onto the iron, the feed-roll actuating-ratchet 110 being advanced by the relative upward movement of the outer end of the pawl-arm 111 which is connected 45 with the stationary arm 113. The quantity of solder fed at each movement may be varied by adjusting the position of the connecting-rod 112 toward or away from the pivot of the pawl-arm so as to vary the 50 stroke thereof.

After the soldering operation is completed and the soldering devices are raised out of engagement with the can-body, the turret is advanced to carry the soldered 55 body to the wiping position F. Above the

carrier-mandrel at said position F, an arm 118 is extended from the hub 114 carried on the upper end of the sleeve 68. Said arm has a radial slot formed therein in which is slidably mounted a body 119 on which is 70 a downwardly projecting finger 120 adapted to engage and wipe the seam of the body at the position F. A bell-crank lever 121 is fulcrumed on a standard 122 extending upwardly from the hub 114, the lower 75 end of said lever being connected by a rod 123 with the slidable body 119, and the inner end of the lever being connected by a rod 124 with the hub 87. By said connections the body 119 is moved outwardly at 80 each downward movement of the shaft 83, and is moved inwardly at each upward movement of said shaft. After the wiping of the seam while at the position F the next movement of the turret carries the mandrel 85 to the ejecting position G. An arm 125 upon the hub 114 extends above the mandrel at said position and on said arm is carried a small roller 126 which is adapted to engage the inclined upper surface of the clamping-plate release-finger 81 to depress said finger and raise the clamping-plate as the mandrel 90 approaches the ejecting position. In the arm 125 is a radial slot in which is slidably mounted a body 127 on which is a downwardly projecting finger 128 adapted to engage the can-body and push the same off the end of the mandrel. The said body 127 is actuated by means of a bell-crank lever 129 fulcrumed on the standard 122, the lower 95 end of the lever being connected with the body 127 by means of a rod 130, the inner end of the lever being connected with the hub 87 by a rod 131, and said parts all operating in the same manner as the similar 100 elements used for actuating the wiping-finger 120.

From the foregoing, the operation of the machine in performing its various functions will be apparent, it being understood that 110 the various parts are so coördinated that the successive operations upon any body-blank will follow each other in the sequence in which they have been described, and that the various operations are simultaneously 115 performed upon the successive blanks passing through the machine, so that a can-body is completed at each series of movements caused by a single revolution of the driving-shafts. It will also be noted that to adapt 120 the machine for making bodies of different diameters it is necessary merely to make adjustments of the magazine and, only when the variation is considerable, of the curling-aperture. For making bodies of different 125 lengths it is necessary to make adjustments of the magazine, of the shearing-plates for notching or trimming the end of the blank, and of the solder-feed when the variation in the length of the seam is considerable. 130

Now, having described my invention, what I claim and desire to secure by Letters Patent is:

1. In a can-body forming machine, a curling device, means arranged to support a body-blank with one end adjacent to said curling device, and a member movable toward the curling device and adapted to engage the end of the body-blank remote from the curling device and from said end alone to push the blank through the curling device, said curling device being arranged transversely to the direction of movement of the blank pusher and adapted to deflect the whole of the advance edge of the blank.

2. In a can-body forming machine, a curling device, rectilinear guiding means having one end adjacent to the curling device, and a member movable through the guiding means toward the curling device, said member being engageable with one end of a body-blank held by the guiding means and adapted to push the blank through the curling device independently of other means, said curling device being arranged transversely to the direction of movement of the blank pusher and adapted to deflect the whole of the advance edge of the blank.

3. In a can-body forming machine, a table, means arranged adjacent to one end of the table to form an arcuate aperture having one end opening at and parallel to the surface of the table, a reciprocatable slide arranged upon the table and adapted to engage a body-blank lying thereon and push the same through the arcuate aperture, and means arranged to receive and support the blank after the same passes through the aperture.

4. In a can-body forming machine, a feed-table, a reciprocatable slide arranged thereon, means arranged near one limit of movement of the slide and forming an arcuate aperture having one end opening at and parallel to the surface of the table, a body-blank magazine carried on the table, means for removing a blank from the magazine and carrying it into the path of the reciprocatable slide, and means upon the slide for engaging and pushing the blank through the arcuate aperture.

5. In a can-body forming machine, a table having channels formed therein, means arranged at one end of the table to form an arcuate aperture intersecting the channels, a reciprocating slide mounted upon the table, and fingers connected with the slide and extending into the channels, the said fingers being adapted to engage a body-blank lying upon the table and push the same through the arcuate aperture.

6. In a can-body forming machine, a table having channels formed therein, means arranged at one end of the table to form an arcuate aperture intersecting the channels,

a reciprocating slide mounted upon the table, and fingers connected with the slide and extending into the channels, the said fingers being adapted to engage a body-blank lying upon the table and push the same through the arcuate aperture, and the ends of the fingers being formed so that the portions thereof engaging the end of the blank will be substantially perpendicular thereto throughout said movement.

7. In a can-body forming machine, a carrier-mandrel, a stationary mandrel, means for placing a body-blank on the stationary mandrel, means for moving the blank from the stationary mandrel onto the carrier-mandrel, and means arranged to gage the lap of the ends of the blank as the same passes onto the carrier-mandrel.

8. In a can-body forming and seaming machine, the combination with a turret, a carrier mounted thereon, and solder-applying devices arranged adjoining the path of the carrier; of a mandrel arranged adjacent to the path of the carrier, means for placing a curled body-blank upon said mandrel, means for moving the blank from said mandrel onto the carrier, and means forlapping and gaging the lap of the ends of the blank as the same passes onto the carrier.

9. In a can-body forming and seaming machine, a carrier-mandrel, a depressible gage arranged in the mandrel, a yieldably impressed clamping-member adapted to close upon the mandrel over the depressible gage, means for curling a body-blank, means alined with the carrier-mandrel for supporting the curled blank, means on said support for separating the ends of the curled blank, said separating means being alined with the depressible gage, means for moving the blank from the support onto the carrier-mandrel, means for moving the clamping-member to a position such as to permit one end of the blank to pass between the same and the depressible gage and thereby lap over the other end of the blank, and means for limiting said lap.

10. In a can-body forming and seaming machine, the combination with means for curling a body-blank to a radius smaller than that of the can-body to be formed; of a supporting mandrel around which the blank is passed by the curling means, said mandrel having a longitudinal projecting member adapted to separate the ends of the curled blank, a carrier-mandrel alinable with the supporting-mandrel, means for moving the blank from the supporting-mandrel onto the carrier-mandrel, means arranged upon and adjoining the said mandrel to direct the ends of the blank intolapping position and to permit the blank to close to such a position, and releasable means for holding the ends of the blank in said lapped position.

11. In a can-body forming and seaming machine, a mandrel having a longitudinal projecting portion, means for curling a body-blank onto said mandrel so that the 5 ends of the blank engage opposite sides of the longitudinal projection portion, the blank being curled to a radius such that it tends to close upon the mandrel, a carrier-mandrel alinable with the first mandrel, a gage carried by said carrier-mandrel at a position thereon coinciding with that of the projecting portion of the first mandrel, means for moving the blank from said mandrel onto the carrier-mandrel, means for directing one 10 end of the blank so that it will rest against the said gage, means for directing the other end of the blank so that it will pass over the gage and overlap the end of the blank engaging the same, means for limiting the extent 15 of said lap, and means for retaining the ends of the blank in lapped position.

12. In a can-body forming and seaming machine, a magazine for body-blanks, means for removing a blank therefrom, means for 20 notching the end of the blank, a stationary mandrel, means for curling the notched blank around said mandrel, a carrier-mandrel, means for passing the curled blank from the stationary mandrel onto the carrier-mandrel, means arranged to permit the 25 resilience of the curled blank to cause the ends thereof to lap as the blank passes onto the carrier-mandrel, means for gaging the lap, means for clamping together the lapped 30 ends, means for moving the carrier-mandrel, and solder-applying means arranged adjacent to the path of the carrier-mandrel.

13. In a can-body forming and lap-seaming machine, a mandrel, a longitudinal gage 35 carried thereby, a clamp-plate disposed adjacent to the gage, means for passing a curled body-blank onto the mandrel so that one end engages the said gage, means for moving the clamping-plate away from the 40 gage sufficiently to permit the other end of the blank to pass between the plate and gage and to lap over the end engaging the gage, means arranged to limit the extent of the lap, the clamp-plate being movable to 45 clamp the lapped ends between it and the mandrel while the ends are so gaged and limited, and means for separating the limiting means and the body-blank.

14. In a can-body forming and lap seaming machine, a mandrel, means for placing upon said mandrel a body-blank curled to a radius smaller than that of the body to be formed, a gage-bar arranged on the mandrel to engage one end of the blank, the said 55 bar being adapted to permit the other end of the blank to spring in over the same and overlap the first end, a gage-plate arranged to engage the latter end of the blank, and a clamping-plate arranged to press the outer 60 lapped end against the inner while they en-

gage the gage-bar and gage-plate, and to hold the lapped ends together.

15. In a can-body forming machine, a feed-table, a body-blank magazine arranged thereon, feeding means for removing blanks 70 from the magazine and actuating the same longitudinally of the table, transverse-feed mechanism arranged to receive blanks from the longitudinal feeding means, curling means with which the blanks are engaged 75 by the transverse feed mechanism, means for receiving and supporting the blanks after they pass the curling means, means for stripping the blanks from said supporting means, and a reciprocating element connected with said stripping means and longitudinal feeding means to simultaneously actuate the same.

16. In a can-body forming and seaming machine, a turret, a plurality of carrier- 85 mandrels sustained thereon, a stationary mandrel, means for actuating the turret to move the carrier-mandrels successively into alinement with the stationary mandrel, means for placing a curled body-blank upon 90 the stationary mandrel, means carried on said mandrel for separating the ends of the blank, means for moving the blank from the stationary mandrel onto the carrier-mandrel alined therewith, and means arranged upon 95 and adjoining said mandrel and operating to permit the ends of the blank to lap, to gage the amount of the lap, and to clamp the lapped ends together.

17. In a can-body forming and seaming 100 machine, a turret, a plurality of carriers mounted thereon, means for actuating the turret to bring each of the carriers successively into a series of positions, gaging and clamp-releasing devices arranged near one 105 of said carrier positions, solder-feeding and solder-applying devices arranged near another of said positions, seam-wiping devices arranged near another of said positions, ejecting devices arranged near another of 110 said positions, a reciprocating actuating-member, and means connecting said member with the gaging, clamp-releasing, solder-feeding, solder-applying, seam-wiping and ejecting devices to simultaneously actuate the same.

18. In a can-body forming machine, a curling device comprising rectilinear guiding members arranged to hold a body-blank between them, a movable element adapted to 120 engage the end of the body-blank and to push the same longitudinally through the guiding members, and a part arranged to deflect all parts of the forward edge of the blank simultaneously and equally from the 125 plane of the guiding members.

19. In a can-body lap-seaming machine, a mandrel, a gage-bar yieldably mounted thereon, a clamp-plate movable adjacent to the gage-bar and pressed normally toward 130

the same, a gage-plate mounted separately from the mandrel and movable into a relation thereto such that the same and the gage-bar may simultaneously engage and 5 determine the lap of the end portions of a body-blank disposed around the mandrel, actuating means for moving the gage-plate toward and away from the mandrel, and means connected with said actuating means 10 for releasing the clamp-plate as the gage-plate is moved to its position adjacent to the mandrel.

20. In a can-body forming machine, a table, means mounted upon the table for engaging the end of a sheet and pushing the same off the table, means disposed at the end of the table for deflecting and curling the sheet when pushed off the table, means disposed over the table for preventing buckling 15 of the undeflected part of the sheet, a stationary horn disposed transversely to the line of movement of the sheet engaging and pushing means in proximity to the deflecting means to receive the curled sheet, means 20 for transporting the curled sheet along the

horn, and actuating means for moving the transporting means in unison with the sheet pushing means, whereby the curling of the sheet and the transportation thereof along the horn are positively timed. 30

21. In a can-body machine, sheet curling mechanism, means for pushing a sheet from its end through said curling mechanism, a stationary member arranged transversely to the line of movement of the sheet pushing means and adapted to receive and support the curled sheet, means for transporting the curled sheet along the supporting means, and driving means connecting the transporting means and sheet pushing means whereby 35 the curling of the sheet and the transportation thereof along the supporting means are positively timed. 40

In testimony whereof I have hereunto subscribed my name in the presence of two witnesses: 45

LEE C. SHARP.
